US00D629882S

(12) **United States Design Patent**
Nguyen

(10) **Patent No.:** US D629,882 S
(45) **Date of Patent:** ** Dec. 28, 2010

(54) **VENT PROTECTING APPARATUS**

(76) Inventor: **Thai Quoc Nguyen**, 3323 Cannongate
CT, San Jose, CA (US) 95121

(**) Term: **14 Years**

(21) Appl. No.: **29/350,348**

(22) Filed: **Nov. 16, 2009**

(51) LOC (9) Cl. **23-04**

(52) U.S. Cl. **D23/386; D14/448**

(58) **Field of Classification Search** D23/386;
454/309, 275-277, 284, 287-291; D14/448-450
See application file for complete search history.

(57) **CLAIM**

The ornamental design for a vent protecting apparatus, as shown and described.

DESCRIPTION

FIG. 1 is a front perspective view of a new design of a vent protecting apparatus;

FIG. 2 is a top plan view thereof;

FIG. 3 is a bottom plan view thereof;

FIG. 4 is an enlarged bottom perspective broken view thereof;

FIG. 5 is an enlarged side elevation view thereof.

FIG. 6 is an enlarged side elevation view of the new design of the vent protecting apparatus mounted on the rear surface of an electronic device.

FIG. 7 is a front perspective view of the new design of the vent protecting apparatus mounted on the rear surface of an electronic device; and,

FIG. 8 is a rear perspective view of the new design of the vent protecting apparatus mounted on the rear surface of an electronic device.

The dashed lines in the drawings represent unclaimed subject matter.
